UNITED STATES PATENT OFFICE.

FRANK S. CROWELL, OF TOLEDO, OHIO, ASSIGNOR TO THE EDWARD N. RIDDLE CO., OF TOLEDO, OHIO, A CORPORATION OF OHIO.

DESIGN FOR A HANGING LAMP.

Application filed June 6, 1923. Serial No. 6,396. Term of patent 3½ years. •

To all whom it may concern:

Be it known that I, FRANK S. CROWELL, a citizen of the United States, residing at Toledo, in the county of Lucas and State of Ohio, have invented a new, original, and ornamental Design for Hanging Lamps, of which the following is a specification, reference being had to the accompanying drawing, forming part thereof.

The figure is a perspective view of a hanging lamp, showing my new design.

I claim:

The ornamental design for a hanging lamp as shown.

FRANK S. CROWELL.
